CLAIM

We claim the ornamental design for a salt block, as shown and described.

DESCRIPTION

FIG. 1 is a top perspective view of a salt block of the present invention;

FIG. 2 is a right side elevation view thereof, the left side elevation view being identical thereto;

FIG. 3 is a front elevation view thereof, the rear elevation view being identical thereto; and,

FIG. 4 is a top plan view thereof, the bottom plan view being identical thereto.

The broken lines in FIGS. 1-4 illustrate portions of the salt block that form no part of the claimed design. In particular, the text "LOGO" appearing in broken lines in FIGS. 1 and 3 forms no part of the claimed design.
